(57) **CLAIM**

The ornamental design for a wristwatch, as shown and
described.

DESCRIPTION

The patent or application file contains at least one drawing
executed in color. Copies of this patent or patent application
publication with color drawing(s) will be provided by the
Office upon request and payment of the necessary fee.

FIG. 1 is a front elevation view of a first embodiment of a
wristwatch showing the new design;

FIG. 2 is a rear elevation view thereof;

FIG. 3 is a bottom plan view thereof;

FIG. 4 is a top plan view thereof;

FIG. 5 is a left side elevation view thereof;

FIG. 6 is a right side elevation view thereof;

FIG. 7 is a top, left side perspective view thereof;

FIG. 8 is a front elevation view of a second embodiment
thereof;

FIG. 9 is a rear elevation view thereof;

FIG. 10 is a bottom plan view thereof;

FIG. 11 is a top plan view thereof;

FIG. 12 is a right side elevation view thereof;

FIG. 13 is a left side elevation view thereof;

FIG. 14 is a top, left side perspective view thereof;

FIG. 15 is a front elevation view of a third embodiment
thereof;

FIG. 16 is a front elevation view of a fourth embodiment
thereof;

FIG. 17 is a front elevation view of a fifth embodiment
thereof;

FIG. 18 is a front elevation view of a sixth embodiment
thereof; and,

FIG. 19 is a front elevation view of a seventh embodiment
thereof.
